UNITED STATES PATENT OFFICE.

WILLIE EUGENE YOUNG AND WILLIE RICHARD GLANCY, OF PITTSBURG, KANSAS.

GUARD AND RERAILING DEVICE FOR RAILROADS.

1,126,155.

Specification of Letters Patent.

Patented Jan. 26, 1915.

Application filed October 8, 1914. Serial No. 865,726.

To all whom it may concern:

Be it known that we, WILLIE EUGENE YOUNG and WILLIE RICHARD GLANCY, citizens of the United States, residing at Pittsburg, in the county of Crawford, State of Kansas, have invented a new and useful Guard and Rerailing Device for Railroads, of which the following is a specification.

The present invention appertains to a guard and rerailing device for railroad tracks, and aims to provide a novel and improved structure of that character adapted to be assembled with a railroad track at the approaches of bridges, trestles, tunnels, curves, crossings, and the like.

This invention contemplates the provision of a novel guard and re-railing device, which may be readily assembled with the rails of a track, and which will efficiently serve its intended purpose or office.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

The invention has been illustrated in its preferred embodiment in the accompanying drawing, wherein:

Figure 1 is a plan view of the device assembled with a railroad track, portions being broken away. Figs. 2 and 3 are enlarged cross sectional views taken on the lines 2—2 and 3—3, respectively, of Fig. 1. Fig. 4 is a longitudinal section taken on the line 4—4 of Fig. 1.

In the drawings, the numeral 1 designates the rails of a railway track, which are mounted as usual upon the ties 2.

In carrying out the present invention, a pair of inner guard rails 3 are mounted upon the ties 2 adjacent the inner sides of the main rails 1, and parallel therewith, and the ends of the inner guard rails 3 converge together, as at 4. A pair of outer guard rails 5 are disposed adjacent the outer sides of the rails 1 and parallel therewith, and have their ends divergent as at 6. The guard rails 3 and 5 are higher than the rails 1, the heads or balls of the guard rails being disposed at the height of a head or ball.

above the treads of the rails 1, as clearly seen in Figs. 2 and 3.

Elongated castings or forgings 7 are disposed between the divergent end portions 6 of the outer guard rails 5, and the rails 1 and elongated rails 8 are disposed snugly between the body portions of the outer guard rails 5, and the rails 1, the terminals of the supplemental rails 8 abutting against the inner ends of the castings or blocks 7. The castings 7 and supplemental rails 8 fit snugly against the adjacent sides of the rails 5 and 1, the inner end portions of the castings 7 and the upper surfaces of the rails 8 being flush with the rails 1, and lying below the heads or balls of the guard rails 5. The outer or remote ends of the castings 7 are curved or inclined as at 9, whereby the castings 7 provide inclines for raising the train wheels upwardly onto the rails.

Castings or forgings 10, similar to the castings or blocks 7, are disposed between the converging end portion 4 of the inner guard rails 3, and the rails 1, the castings or blocks 10 fitting snugly against the converging portions of the guard rails 3 and being spaced from the inner sides of the rails 1, to accommodate the wheel flanges at the inner sides of the rails 1. The castings 10 like the castings 7, are tapered from their outer to their inner ends, and the outer ends of the castings 10 are inclined or curved, as at 11, for raising the car wheels onto the rails. The upper surfaces of the castings 10 at the inner ends of the said castings, are disposed below the treads of the rails 1.

Spacers 12 are disposed between the body portions of the guard rails 3 and castings 10 and the rails, and lateral bolts 15 are engaged through the webs of the rails 3, 1 and 5, and engage through the castings 7 and 10, and the spacers 12, to secure or clamp the said parts firmly together.

The guard rails 3 and 5 being disposed at the sides of the respective rails 1 of the track, and having their treads spaced above the treads of the rails 1, will naturally tend to prevent the derailing of the train wheels. It is also evident that any derailed wheels in approaching the guard and rerailing device, will ride upwardly upon the inclines at the respective end of the device, to carry the train wheels upwardly onto the rails. Should the train wheels be derailed to one

side of the rails 1, the wheels at one side will ride upon the corresponding outer guard rail 5, and may readily slide back over the corresponding rail 8 onto the proper rail 1 to rerail the wheels. The inner guard wheels 3 prevent the excessive lateral movement of the train wheels, so that they will not pass or jump over the outer guard rails 5.

10. The present device may be employed at various points along a railroad track, and is of advantage in several respects, as will be obvious to those versed in the art, and familiar with the circumstances. The device 15 may be extended through bridges and tunnels, or along curves, of any length.

Having thus described the invention, what is claimed as new is:—

20. The combination with a railroad track, of a guard and rerailing device including inner guard rails disposed adjacent and parallel with the track rails and having their ends converging, outer guard rails disposed adjacent the outer sides of the track rails and parallel therewith and having their ends divergent, the guard rails being higher than the track rails and having their heads spaced above the treads of the track rails, members disposed snugly between the di-

vergent end portions of the outer guard rails 30 and the track rails, supplemental rails disposed snugly between the outer guard rails and track rails, and terminally abutting against the inner ends of the said members, the said supplemental rails and inner end 35 portions of the said members being flush with the track rails, the outer ends of the said members being inclined, members disposed between the converging end portions of the inner guard rails and the track rails, 40 the second mentioned members fitting snugly against the converging end portions of the inner guard rails and being spaced from the track rails and having their outer ends inclined, spacers disposed between the track 45 rails and the inner guard rails and between the track rails and the second mentioned members, and bolts engaged through the webs of the guard and track rails and through the said members and spacers.

In testimony that we claim the foregoing as our own, we have hereto affixed our signatures in the presence of two witnesses.

WILLIE EUGENE YOUNG.
WILLIE RICHARD GLANCY.
